UNITED STATES PATENT OFFICE.

LOUIS GODDU, OF WINCHESTER, MASSACHUSETTS, ASSIGNOR TO GORDON MCKAY, OF NEWPORT, RHODE ISLAND, AND JAMES W. BROOKS, OF CAMBRIDGE, MASSACHUSETTS, TRUSTEES.

NAIL-MAKING MACHINE.

SPECIFICATION forming part of Letters Patent No. 269,279, dated December 19, 1882.

Application filed June 10, 1882. (No model.)

To all whom it may concern:

Be it known that I, LOUIS GODDU, of Winchester, county of Middlesex, State of Massachusetts, have invented an Improvement in 5 Nail-Making Machines, of which the following description, in connection with the accompanying drawings, is a specification.

My invention has for its object the construction of a machine for the production of headed 10 and corrugated nails, chiefly for use for boots and shoes and leather-work.

In this my invention the blanks for the nails are cut from a metal strip and moved by a transerrer between the dies, where the body 15 of the blank is corrugated and one end is upset to form a head. The blank, as it is cut from the metal strip, is pressed down upon a directing device made with a sharp edge to cut into one side of or enter a groove in the blank, the 20 said directing device holding the blank firmly between it and a flat or horizontal surface extended from one side of the upper die, in which the blank is corrugated and headed. The blank is moved horizontally between the directing 25 device and the said horizontal surface above it by means of the transerrer, which acts upon the rear side of the blank, near its ends, thus feeding the blank squarely into the space between the dies; but to prevent the blank 30 being thrown beyond the center of the said dies I have provided a stop or blank-arresting device, which closes the gap at the farthest side of the open dies when the blank is entered between them. As the blank enters 35 the dies it is fed beyond the end of the directing device, which, pressed upward by a spring and having its end entered within a recess at the side of the lower die, is elevated so that the end of the directing device comes into position at the rear side of the blank, the end of 40 the directing device and the forked end of the stop aligning the blank in the dies before or as the dies close upon the blank. The header is shaped to countersink the heads of the 45 nails. The groove formed in the side of the blank and entered by the directing device aids very materially in insuring the correct presentation of the single blanks between the dies to be corrugated and headed; but, if desired, the strip may be creased at one side lon-

gitudinally before being fed into the machine, or may be partially creased or grooved in the machine as the strip is passed to the cutters to have a blank separated from it.

Figure 1 represents a front end elevation of 55 the principal part of a nail-making machine embodying my invention. Fig. 1^a is a development of cam A⁵; Fig. 2, a partial rear side elevation of Fig. 1; Fig. 3, a partial top view broken out to show one of the operating-cams; 60 Fig. 4, a section on the line x¹ x¹, Fig. 1; Fig. 5, a section on the line x² x², Fig. 1; Fig. 6, a detail of the bed upon which the strip rests, with the transerrer shown as acting upon the edge of a blank and as feeding it forward; 65 Fig. 7, a sectional detail in the dotted line x³, Fig. 2, showing the dies and the device for throwing the nails from the dies after the latter are opened; Fig. 8, an enlarged vertical section of the dies, showing the projections 70 thereon for corrugating the body of the blank, and in which the head is upset. Fig. 9 is a partial vertical section on the dotted line x⁴, Fig. 5, looking toward the left, the said figure showing a blank held between the directing device 75 and the horizontal extension of the upper die; Fig. 10, a partial section on the line x⁵, Fig. 4; Fig. 11, a partial section on the dotted line just below it; Figs. 12 and 13, sectional details of the end of the lever which carries the 80 heading device, with the heading device held therein; Fig. 14, an enlarged detail of the nipple and screw for holding the heading device; Fig. 15, a face view of the under die for corrugating and holding the blank while being 85 headed, and of the directing device; Fig. 16, a sectional detail of the stop for arresting the blank at the rear side of the dies; Fig. 17, another view of the same; Fig. 18, a partial vertical cross-section on the line x⁶, Fig. 3, taken 90 through the guideway for the strip to be cut into blanks; Fig. 19, a partial section on the line x⁷, Fig. 3, showing the feeding-rollers which move the strip intermittently. Fig. 20 shows a pawl and ratchet for moving the feeding-rollers. Fig. 21 is a broken detail of the pawl shown in Fig. 20, to illustrate the spring 95 for holding it down upon the ratchet. Fig. 22 shows the under side of the strip as it will appear after passing the feed-rollers. Fig. 23 100

shows a blank cut from the strip; Fig. 24, a nail made from the blank, and Fig. 25 an under side view of the upper die.

The frame-work A of the machine, of proper shape to contain the working parts, has suitable bearings for the main shaft A², having upon it the cam-hubs A³ A⁴ A⁵. The belt-wheel A⁶ is connected with the cam-hub A³ (see Fig. 3) by a screw-thread. The cam-groove a¹ receives a roller or other stud, a², of an arm, a³, of a three-armed lever, B, having its fulcrum on a rigid sleeve, B², (see Fig. 7,) the said lever being held thereon by a nut, b. The ends of lever B have toothed sectors a⁴ a⁵, which engage sector-gears b¹ b² on the rock-shafts b³ b⁴, grooved parallel with their axes (see Fig. 4) to receive the ball-like ends of like links b⁵, the opposite ball-like terminations of which engage grooves of like cross-section in the followers C 15 C', which carry the two dies c² c³, between which the blank is shaped into a nail.

The follower C has fitted to it the steel blade d, made adjustable by the screw d² and nut d³, the said blade serving as the movable member 25 of the cutting mechanism for severing a blank, d⁴, from the strip d⁵, the under member of the said strip-cutting mechanism being the upper corner of the end of the steel or hardened block d⁶, which constitutes the bottom plate of the 30 guideway for the strip, down upon which block the strip is pressed by the shoe or plate e and rod e', held under greater or less pressure by the spring e², made adjustable by the screw e³.

(See Fig. 4.)

35 The follower C' (see Figs. 4 and 9) has fitted to it the shank f of the directing device f', having a knife-like edge, and extended forward, (see Fig. 15,) with its front end in a notch made in the side of the lower die, c³, at its face. This 40 directing device is normally held up by a spiral spring, f², on its shank, so that when the followers C C' are moved to separate the dies c² c³ the upper edge of the directing device will strike against the end of the strip projected 45 beyond the end of the block d⁶. The dies c² c³ are fastened to the followers by suitable screws, g g, and caps g². (See Figs. 10, 11.) A block, f³, on the shank f, entered within a slot in the follower C', keeps the directing device f' in 50 proper line.

The groove in the cam-hub A⁵ receives a roller-stud, h, on an arm, h', of a rock-shaft, h², having a second arm, h³, connected (see Fig. 3) by screw or pin h⁴ with the link h⁵, having a circular end, (see Figs. 1 and 12,) by which to attach it to the lower end of the lever h⁶, which carries the heading device D. The lever h⁶ is attached by screw or bolt h⁷ with the yoke h⁸, adjustably pivoted upon the frame-work by 55 the screws h⁹, so as to adjust the lever and insure the correct entrance of the header into the open space between the dies c² c³. The header has its front end shaped to indent or countersink the head of the blank as the latter is headed and upset in the die-space 2. (See Fig. 15.) The shank of the header is extended

into the nipple D³ against the abutting-screw D⁴, and the nipple, screw-threaded externally, (see Figs. 12 and 14,) is screwed into an opening between an ear on lever h⁶ and the block 70 D⁷, held in place by a screw, D⁸. The screw D arrests the backward movement of the header in the nipple, and if the header breaks or a new one is to be employed the nipple may be removed, and then the screw D⁴ and the header 75 may be driven out in the direction of the arrow in Fig. 14 and a new one supplied.

The cam-hub A⁴ has at its opposite faces two cam-grooves, i¹ i², the one i¹ being shown in full lines, Fig. 5, and the one i² in dotted lines, Fig. 4. The cam-groove i² receives a roller or other stud, i³, (see dotted lines, Fig. 4,) of a lever, i⁴, having at its upper end a pin, i⁵, (see Figs. 3 and 20,) which enters a notch in the arm i⁷, connected by pin i⁸ with the pawl-carrier i⁹, loose on the hub of the ratchet m, secured to the shaft m³, having the lower feed-roller, m⁴. The pawl-carrier i⁹ is held upon the hub of the ratchet by the washer m² and screw. The pawl 4 is held in engagement with the 85 ratchet-wheel m by the spring 5, placed in a recess in the arm i⁷. The opposite end of shaft m³ has a pinion, m⁵, which engages a pinion, m⁶, of like size on the shaft m⁷ of the upper feed-roller, m⁸, so that the pawl and ratchet move 90 the feed-rollers, properly milled or fluted, so that they, in operation, will act to move forward intermittently the strip d⁵, which will be placed between them.

The block d⁶, forming the lower member of 100 the strip-cutting device, and also the bottom plate of the guide, has two longitudinal passages made through it from end to end for the reception of the transerrer n, composed of two wires held in a block, 6, pivoted between pointed 105 screws n¹, (see Fig. 3,) at the upper end of the lever n², pivoted at n³, (see Fig. 5,) and having a roller or other stud which enters the cam-groove i, before referred to. The wires of the transerrer are stiffened and kept true by a 110 block, 7, applied to them. When it is desired to stop the feed the arm i⁷ is lifted from the pin i⁵ of lever i⁴.

The stop p, to arrest the block at the farthest 115 side of the dies c² c³, is notched vertically at its front end, as at 10, (see Fig. 16,) and is connected by the screw p² with the slide-rod p', actuated in one direction positively by the arm p³, connected with the rock-shaft p⁴, surrounded 120 by a spiral spring, p⁵, the other end of the said rock-shaft having attached to it a second arm, p⁶, which, when the dies c² c³ are fully opened, rests on the adjustable lug p⁷, attached to the sector-gear b², fast on the rock-shaft b⁴. The spring p⁵, when free to act, moves the rod p' 125 and stop p forward, so that the inclined upper and lower sides of the said stop (see Fig. 17) meet the inclined edges at the rear sides of the dies, the beveled surfaces of the stop and dies being such with relation to each other that the 130 front end of the stop will be arrested at the rear of the die-grooves. As the dies c² c³ are

closed together the stop is gradually pulled back by the lug p^7 acting on arm p^6 . The nail, having been finished, is thrown from between the dies $c^2 c^3$ by the ejector r , (see Fig. 7,) made 5 as a rod having a collar, r^1 , acted upon by a spiral spring, r^2 , abutted against a threaded nut, r^3 . The outer end of the ejector has screwed upon it a long tubular check-nut, r^5 , adapted to reciprocate in a guide, r^6 , secured to the block r^7 , attached to the bracket r^8 . The 10 ejector has adjustably connected with it a collar, r^4 , having an annular groove, which receives the forked end of a lever, r^9 , pivoted at r^{10} , and having a loose or swiveling block, r^{12} , which is acted upon by the side cam, r^{13} , attached to belt-pulley A^6 . The cam r^{13} has one 15 end inclined, as at 12, Fig. 3; but its opposite end has at 10, Fig. 2, an abrupt shoulder, from which the block r^{12} drops when the dies $c^2 c^3$ are opened, and the ejector is to be operated by spring r^2 to throw the headed nail out from between the dies. 20

The upper side of block d^6 may have a cutting-rib, 14, to enter and assist in making a 25 groove in the strip to be entered by the directing device as the blank is cut off.

The die c^2 has a horizontal extension, 15, (see Fig. 25,) against which the upper side of the blank d^4 may be pressed, and the horizontal 30 extension will be provided with a recess to prevent dulling the edge of the directing device when the latter meets the said die.

The strip to be cut into blanks and made into 35 nails will be passed between the shoe or plate e and the block d^6 , and will be fed forward for the proper distance by the feed-rollers, when the latter will be stopped, leaving the strip projected beyond the end of the block, the followers and dies $c^2 c^3$ being then fully opened. The 40 followers will then be moved toward each other. The cutter member d will descend on the upper side of the strip and sever the same transversely close to the front end of the block d^6 , which is the lower cutter member.

45 The directing device is held up by spring f^2 against the blank, and as the blank is severed from the strip the cutter d , continuing to descend, presses the blank d^4 down upon the sharp or thin upper edge of the directing device. The blank is depressed sufficiently to place its rear side opposite the ends of the two wires forming the blank-transferrer, and the latter is then moved forward, pushing the blank before it, while the blank is held between 50 the sharp edge of the directing device and the horizontal extension 15 of the upper die. During this movement the dies $c^2 c^3$ are sufficiently far apart to receive between them the blank d^4 , and the rear side of the space between the dies is

55 closed by the stop p . As the transferrer pushes the blank beyond the end of the directing device f' , the latter, acted upon by its spring, is thrown up behind the blank, and the latter is then held near the center of its length by the end 60 of the directing device, while the opposite side of the blank rests against the forked end of

the stop p . While so held the dies close together upon the blank, inclosing the body of the blank between the said dies, which, by their corrugated surfaces, corrugated the said blank 70 for the shank of the nail to be produced. The dies having closed upon the blank, the header D is thrown forward to upset or head the blank in the space 2 of the dies. The head having been formed and the dies having been partially 75 opened, the ejector is thrown forward to remove the nail from between the dies $c^2 c^3$.

To insure the discharge of the nail in the proper direction, I have provided an inclined plate, s , on an arm, s' , placed on the shaft h^2 , 80 it having a spring, s^2 , by which to keep the plate s down in place. A nail striking the inclined under side of plate s will be deflected down into a chute or box (not shown) between it and the floor on which the machine will stand. 85

The face-plates t t' , held by screws t^2 , keep the followers c c' in their guideways. The strip d^5 is omitted from Figs. 3, 4, and 5, but is shown in Fig. 9.

The adjustment of the collar r^4 on the ejector 90 enables me to cause the same to be projected forward just the proper distance to meet the point of the nail then between the dies and to be removed, the said nails being of greater or less length, projecting more or less back of the die.

I claim—

1. The followers and their attached dies $c^2 c^3$, the rock-shafts $b^3 b^4$, and the connecting-links b^5 , combined with the toothed lever B , to operate the said rock-shafts, substantially as described. 100

2. The block d^6 and shoe or presser to keep the strip down in its guideway, combined with the reciprocating followers, their attached dies, and the cutter member d , to operate substantially as described. 105

3. The block d^6 , constituting the under member of the cutter, the follower, and the attached movable upper cutting member, combined with the directing device having an edge to enter the blank severed from the strip, substantially as described. 110

4. The cutting mechanism to sever the strip transversely, and the directing device having a thin or sharp edge, upon which the blank is pressed and held, combined with the transferrer to act upon the said blank each side the directing device and move it toward the dies, substantially as described. 115

5. The cutting mechanism to sever the strip transversely, the directing device having a thin or sharp edge upon which the blank is pressed, the upper die, c^2 , the horizontal extension or part 15 at its side and above the directing device, and the lower die, c^3 , combined with the transferrer, to act upon the blank and place it in the space of the dies, substantially as described. 120

6. The cutting mechanism to sever the strip, 130 the dies $c^2 c^3$, and the transferrer, to act upon the edge of the blank near its ends and place

- it in the space of the said dies, combined with the header to head the said blank, substantially as described.
7. The directing device to support the under side of the blank as it is being fed forward, combined with the die c^2 , having a notch, into which the front end of the said directing device is entered, substantially as described.
8. The directing device to support the under side of the blank as it is being fed forward, a spring to force the directing device toward the blank, the dies $c^2 c^3$, and the transerrer, to act upon the blank and move it beyond the end of the directing device into the die-space, combined with the stop to arrest the movement of the blank in line with the space in the said dies which is to receive the blank, substantially as described.
9. The stop p , forked at its front end, and the dies $c^2 c^3$, combined with the transferring device, substantially as described.
10. The stop p , forked at its front end, and the dies $c^2 c^3$, combined with the spring-supported directing device, adapted to rise behind the blank close to the die-space as the blank is to be compressed in the said die-space, substantially as described.
11. The dies $c^2 c^3$, the stop, and its rod p' , combined with the arm p^3 , rock-shaft p^4 , arm p^6 , and means to move them at the proper times, substantially as described.
12. The dies $c^2 c^3$ and the header to head the blank therein, the rock-shafts $b^3 b^4$, links b^5 , and toothed lever B to operate the rock-shafts, combined with the ejector to throw the headed nail from between the dies, substantially as described.
13. The dies $c^2 c^3$, the ejector, its actuating-spring, the flanged nut or collar p^4 , and the lever r^9 , combined with a cam to actuate the said lever and retract the ejector, substantially as described.
14. The ejector, the collar p^4 , and the long tubular check-nut, combined with the guide r^6 for the nut, substantially as described.
15. The feed-rollers, their carrying-shafts, the pawl i^9 and ratchet m , and the notched arm i^7 , combined with the lever to move the said arm and pawl-carrier when the arm is engaged with the said lever, substantially as described.
16. The lever n^2 and transerrer connected therewith, composed of two rods, combined with the block h^6 , which serves as a guide for the said transerrer, as shown and described.
17. The rock-shaft h^2 , arm h^3 , link h^5 , and lever h^6 , combined with the header connected therewith, substantially as described.
18. The header and the nipple in which the shank of the header is entered, combined with the removable screw to act against the inner end of the said header, substantially as described.
19. The dies $c^2 c^3$, the header, and the ejector to remove the headed nail from between the dies, combined with the shield or deflector s , substantially as and for the purpose described.
- In testimony whereof I have signed my name to this specification in the presence of two subscribing witnesses.
